UNITED STATES PATENT OFFICE.

OLIVER C. ARMSTRONG AND JOHN R. STEPHENSON, OF LOS ANGELES, CALIFORNIA.

COMBINATION IRONING BOARD AND CHAIR.

Application filed April 28, 1926. Serial No. 105,275.

This invention relates to household articles and has particular reference to a combination ironing board and chair.

An important object of the invention is to provide a device which may be arranged to form a comfortable chair and when desirable converted to provide a convenient and practical ironing board.

A further object of the invention is to provide a device of the above character which may be very easily converted from a chair to an ironing board and provide durable and efficient structures in either form.

Another object of the invention is to provide a device of this character which is of comparatively simple design and which may be placed upon the market at a relatively low cost.

Other objects and advantages of this invention will become apparent as the description progresses.

In the accompanying drawings forming a part of this specification and in which like numerals are employed to designate corresponding parts throughout the same:

Figure 1 is a side elevation of the structure comprising our invention arranged to serve as a chair,

Figure 2 is a front elevation of the same, 30 Figure 3 is a top plan view of the device converted to form an ironing board,

Figure 4 is a vertical sectional view taken on the line 4—4 of Figure 2 looking in the direction indicated by the arrows,

Figure 5 is a longitudinal sectional view taken on the line 5—5 of Figure 3 looking in the direction indicated by the arrows,

Figure 6 is a fragmentary sectional perspective view showing the construction of a 40 part of the seat member,

Figure 7 is an enlarged transverse sectional view showing the movable board structure,

Figure 8 is a similar view showing the seat 45 structure, and

Figure 9 is a fragmentary sectional perspective view of a portion of the supporting frame.

In the drawings, wherein for the purpose 50 of illustration is shown the preferred embodiment of our invention, the numeral 10 generally designates a supporting frame comprising a pair of parallel vertically extending side beams 11 of preferably rectangular construction. These side beams are connected by a plurality of transversely

extending bars 12 secured to the rear edges of the beams so as to provide a firm frame structure. This frame is preferably of wood 60 in construction suitably finished to present a pleasing appearance. The inner sides of the side beams 11 are provided with longitudinally extending grooves 13, these grooves being arranged in opposed relation and extending from a point slightly above the lower 65 extremity of the respective beam to approximately the center portion, the upper extremities of the grooves being forwardly directed on a curved line as indicated at 14. The foregoing construction provides a rectangular support frame adapted to assume a vertical position, the lower ends of the side beams being adapted to rest upon the floor while the intermediate portion is adapted to support convertible parts capable of 70 being employed as an ironing board or a chair.

Arm rests 15 are connected to the beams by means of hinges 16, permitting the arm rests to be swung, from a horizontal position, in a downward direction to a substantially vertical position. For purposes of convenience, it is desirable that these arm rests be of comparatively wide construction, and with this in mind, the rear extremities of 85 the rests 15 are recessed for connection with the side respective beams providing a rearward extension projecting at the side of the respective beams.

Chair legs 17, which are bowed inwardly 90 adjacent their inner ends to enhance the appearance thereof and prevent obstruction when the structure is being used as an ironing board, are braced by a transversely extending rod 18 and are connected to the under side of the arm rests 15 by hinges 19, arranged so as to permit the legs to be swung forward to a position in alignment with the rests. This construction of the arm rests and legs will permit these members to be 95 adjusted to position in mutual alignment and to assume an angular position relative to the support frame 10, as shown in dotted lines in Figure 1.

In order that the arm rests may be firmly 105 supported in their positions of adjustment, each arm carries a brace bar 20 hingedly connected to the under side of the arm adjacent the connection of the respective chair leg and extending at an angle of inclination 110 toward the side beams. The lower ends of these brace bars are slidably engageable in

vertical recesses 21 formed in the forward edges of the side beams 11. The upper extremities of these recesses are preferably of arcuate formation as indicated at 22 and the outer ends of the brace bars are rounded so that the outer ends of the brace bars may be snugly fitted in the said ends of the recesses when the parts are adjusted as in Fig. 4. Supporting members 23 are hinged 10 in the rear sides of the recesses and are adapted, when swung inwardly to seat within the lower portions of the recesses. These members are arranged to extend from the lower portions of the recesses to a point somewhat 15 below the upper ends of the recesses so as to provide above the members 23 suitable for the reception of the outer or rear ends of the brace bars 20. It will be noted, that the members 23 may be swung from a position 20 in engagement with the recesses 21, as shown in Fig. 1, to position out of engagement in the recesses as shown in Fig. 9, thus permitting vertical slidable movement of the brace bars 20 so as to support the arm 25 rests in elevated or lowered positions. In order that the lower or rear ends of the brace bars 20 will be retained in movable engagement in the recesses 21, a transverse brace 24 is secured adjacent the lower ends 30 thereof, this brace preventing lateral displacement of the bars. These bars are further guided in their vertical movement by the provision of studs 20' secured to the lower portions of the bars 20 and adapted 35 to travel in narrow vertically extending groove 21'. When it is desirable to lower the arm rests 15 so that they are in continuous alinement with the chair legs 17 in an inclined position relative to the supporting 40 frame, the members 23 are swung out of engagement in the recesses 21 to permit the brace bars being lowered so that their lower extremities are disposed in the lower portions of the recesses.

An ironing board 25 is connected, in a manner to be presently explained, to the frame 10 and is adjustable to position to constitute a back rest for the chair structure as shown in Figs. 1, 2 and 4 or to position to 45 serve its original purpose, as shown in Figs. 3 and 5. This is preferably accomplished by the provision of a cleat 26 at the rear end of the board having laterally extending projections 27 at its ends terminating in pintles 28 slidably engaging in the longitudinal grooves 13 formed in the side beams of the supporting frame. This construction 50 will permit the rear end of the ironing board 25 to be adjusted between elevated and lowered positions. Hinged as at 30 to the intermediate portion of the ironing board 25 and extending from the under side thereof, 55 is a substantially rectangular seat board 29. This seat board is attached to the ironing board at a suitable height above the low-

er or rear end of the board to provide a convenient chair seat when the ironing board is in a vertical position. The outer free end of the seat board 29 has secured to it a transversely extending bar 31 provided at its ends 70 with studs. The studs engage in longitudinally extending grooves 32 formed in the upper portions of the chair legs 17, the upper extremities of these grooves terminating in rearwardly directed arcuate portions 33. 75 Secured to the ironing board 25 adjacent the connection of the seat board 29 therewith is a block 34 which, in the position of adjustment of the ironing board to serve as a chair back is adapted to contact with the transverse brace 24 so as to prevent accidental movement of the braces 20 and likewise prevent forward tilting of the ironing board. 80

When using the structure as a chair the ironing board 25 is tilted to a vertical position within the supporting frame and is disposed between the side beams 11. The arm rests and legs are adjusted to assume the positions shown in Figs. 1, 2 and 4 so that the arm rests extend horizontally forward from the side beams. The brace bars 20 will now be in elevated position with their ends resting on the upper extremities of the members 23. The seat board 29 will assume a horizontal position between the 95 chair legs and, may, when desirable, be provided with cushions or pads to provide a convenient seat. When the structure is arranged in this manner the ironing board will serve as a convenient back rest 100 affording a strong and comfortable chair. The device will ordinarily be adjusted or arranged for use as a chair but may be quickly converted to provide an ironing board and stand. 105

When it is desirable to employ the apparatus as an ironing board or table, the members 23 are swung outwardly as shown in Fig. 9 and the brace bars 20 are then permitted to slide downwardly, the chair legs and arm rests being adjusted to mutually alined positions as clearly shown in Figures 3 and 5, the brace bar studs 20' resting at the lower extremities of the grooves 21'. The ironing board is tilted from a vertical 110 to a horizontal position, being braced at its intermediate portion by means of the seat 29. The projecting studs 32 carried by the forward corners of the seat engage the upper arcuate extensions of the grooves 33 and 115 being in this manner held against displacement. It is apparent, from the foregoing, that a conveniently convertible structure is provided. The structure may also be advantageously employed as a card or tea table 120 of longitudinal formation. 125

It is to be understood that the form of our invention herewith shown and described is to be taken as the preferred example of the same and that various changes as to 130

the shape, size and arrangement of parts may be resorted to without departing from the spirit of the invention, or the scope of the subjoined claims.

5 Having thus described our invention, we claim:

1. A device of the class described comprising a support frame, arm rests hingedly mounted on the sides of the frame, chair legs hingedly connected adjacent the outer extremities of the arm rests, movable braces carried by the arm rests, a longitudinal board tilttable relative to the frame adapted to provide a chair back in one position and an ironing board in another position of the device, and a seat member connected with the board.

2. A combination ironing board and chair comprising, a supporting frame, arm rests hingedly connected to the intermediate portion of the frame, a pair of chair legs connected to the arm rests and adapted to be adjusted to supporting position and to position in alinement with said arm rests, brace members connected to the arm and adapted to support the same in both positions of adjustment, a forwardly tilttable board adapted to be moved to a vertical position in the frame to constitute a chair back and to assume a horizontal position to constitute an ironing board, and a seat member connected with the said board.

3. A combination ironing board and chair, comprising in combination, a vertical supporting frame, arm rests hingedly secured to the supporting frame and movable from a horizontal to a downwardly and forwardly inclined position, legs hingedly connected adjacent the outer extremities of the arm rests for supporting the same, brace members carried by the arm rests, rest members mounted on the sides of the supporting frame engageable by the brace members, the sides of the supporting frame having grooves therein, a board having pintles engaging in the grooves in the sides of the supporting frame, the said board being tilttable from a vertical to a horizontal position, and a chair seat hingedly connected to the board, to extend horizontally therefrom when the board is in upright position.

4. A combination ironing board and stand comprising a vertical supporting frame, arm rests hingedly secured to the supporting frame, legs hingedly connected to the arm rests, the said arm rests and legs being movable from right angular to aligned positions, brace bars hingedly secured to the arm rests adapted to brace the rests, the said frame including side members having grooves therein, an ironing board provided with pintles engaging in the grooves in the side members of the supporting frame, a seat board hingedly secured to the intermediate portion of the ironing board adapted to con-

stitute a seat in the vertical position of the ironing board to constitute a vertical brace for the ironing board in the horizontal position of the latter.

5. A combination ironing board and chair comprising a vertically positioned supporting frame having grooves formed in the side members thereof, arm rests hingedly connected with the side members, legs hingedly connected with the arm rests, brace bars hingedly connected with the arm rests, an ironing board having pintles engaging in the grooves in the side members of the supporting frame, the said ironing board being movable from a vertical position within the frame to a horizontal forwardly extending position, and a seat member hingedly connected to the intermediate portion of the ironing board and adjustable to constitute a seat in the vertical position of the ironing board and to constitute a brace member for the board in the horizontal position of the board.

6. A convertible ironing board and chair comprising an upright frame including side members, a board adjustably connected with the said frame to assume an upright position between the said side members and constitute a chair back and also to assume a horizontal position to constitute an ironing board, arm rests hingedly connected to the side members of the frame, and adjustable to assume a position extending forwardly beyond the said board and constitute arm rests and to assume a forwardly and downwardly inclined position to constitute a brace, leg members hingedly connected with the arm rests inwardly of the outer ends of the said arm rests and adjustable to assume an upright position beneath the arm rests to support the said rests in their first mentioned position of adjustment, the said leg members being also adjustable about their hinges to extend substantially in alinement with the arm rests when the latter are in their last mentioned positions of adjustment, and a seat member hingedly connected with the said board to extend horizontally therefrom in the upright position of adjustment of the board and constitute a seat and to extend at an angle from the board and between the same and the leg members in the latter positions of adjustment of the board and leg members to constitute a supporting brace for the board in said latter position of adjustment thereof.

7. A convertible ironing board and chair comprising an upright frame including side members, a board adjustably connected with the said frame to assume an upright position between the side members and constitute a chair back and also to assume a horizontal position to constitute an ironing board, arm rests hingedly connected to the side members of the frame and adjustable to

assume a position extending forwardly beyond the said board and constitute arm rests and to assume a forwardly and downwardly inclined position to constitute a brace, leg members hingedly connected with the arm rests inwardly of the outer ends of the said arm rests and adjustable to assume an upright position beneath the arm rests with their upper ends abutting against the under sides of the rests to support the said rests in their first mentioned position of adjustment, the said leg members being also adjustable about their hinges to extend substantially in alinement with the arm rests when the latter are in their last mentioned positions of adjustment and engaging, in such position of adjustment, at their forward sides, against the under sides of the respective arm rests to maintain the alinement of the parts, a seat member hingedly connected with the said board to extend horizontally therefrom in the upright position of adjustment of the board and constitute a seat and to extend at an angle from the board and between the same and the leg members in the latter positions of adjustment of the board and leg members to constitute a supporting brace for the board in said latter position of adjustment thereof, and means slidably and pivotally connecting the forward corners of the seat member with the said legs.

8. A convertible ironing board and chair comprising an upright frame including side members, a board adjustably connected with the said frame to assume an upright position between the side members and constitute a chair back and also to assume a horizontal position to constitute an ironing board, arm rests hingedly connected to the side members of the frame and adjustable to assume a position extending forwardly beyond the said board and constitute arm rests and to assume a forwardly and downwardly inclined position to constitute a brace, leg members hingedly connected with the arm rests inwardly of the outer ends of the said arm rests and adjustable to assume an upright position beneath the arm rests with their upper ends abutting against the under sides of the rests to support the said rests in their first mentioned position of adjustment, the said leg members being also adjustable about their hinges to extend substantially in alinement with the arm rests when the latter are in their last mentioned positions of adjustment and engaging, in such position of adjustment, at their forward sides, against the under sides of the respective arm rests to maintain the alinement of the parts, a seat member hingedly connected with the said board to extend horizontally therefrom in the upright position of adjustment of the board and constitute a seat and to extend at an angle from

the board and between the same and the leg members in the latter positions of adjustment of the board and leg members to constitute a supporting brace for the board in said latter position of adjustment thereof, the legs being provided in their opposing sides with longitudinal grooves near their upper portions having angularly turned upper ends, and pintles upon the forward corners of the seat member working in said grooves, the pintles being engageable in the lower ends of the grooves in the vertical position of adjustment of the said legs whereby to support the seat member in its horizontal positions of adjustment and the said pintles being engageable in the angularly directed upper ends of the grooves in the last mentioned position of adjustment of the legs in which position the said seat member constitutes a supporting brace for the board.

9. A convertible ironing board and chair comprising an upright frame including side members, a board adjustably connected with the said frame to assume an upright position between the said side members and constitute a chair back and also to assume a horizontal position to constitute an ironing board, arm rests hingedly connected to the side members of the frame, and adjustable to assume a position extending forwardly beyond the said board and constitute arm rests and to assume a forwardly and downwardly inclined position to constitute a brace, leg members hingedly connected with the arm rests inwardly of the outer ends of the said arm rests and adjustable to assume an upright position beneath the arm rests to support the said rests in their first mentioned position of adjustment, the said leg members being also adjustable about their hinges to extend substantially in alinement with the arm rests when the latter are in their last mentioned positions of adjustment a seat member hingedly connected with the said board to extend horizontally therefrom in the upright position of adjustment of the board and constitute a seat and to extend at an angle from the board and between the same and the leg members in the latter positions of adjustment of the board and leg members to constitute a supporting brace for the board in said latter position of adjustment thereof, and braces hingedly connected with the arm rests and extending downwardly and rearwardly and coacting with the side members of the upright frame.

10. A convertible ironing board and chair comprising an upright frame including side members, a board adjustably connected with the said frame to assume an upright position between the said side members and constitute a chair back and also to assume a horizontal position to constitute an ironing board, arm rests hingedly connected to the side members of the frame, and

adjustable to assume a position extending forwardly beyond the said board and constitute arm rests and to assume a forwardly and downwardly inclined position to constitute a brace, leg members hingedly connected with the arm rests inwardly of the outer ends of the said arm rests and adjustable to assume an upright position beneath the arm rests to support the said rests in their first mentioned position of adjustment, the said leg members being also adjustable about their hinges to extend substantially in alinement with the arm rests when the latter are in their last mentioned positions of adjustment, a seat member hingedly connected with the said board to extend horizontally therefrom in the upright position of adjustment of the board and constitute a seat and to extend at an angle from the board and between the same and the leg members in the latter positions of adjustment of the board and leg members to constitute a supporting brace for the board in said latter position of adjustment thereof, the side members of the upright frame having vertical grooves in the lower portions of their outer sides, braces hingedly connected with the arm rests, pintles carried by the lower ends of the braces and working in said grooves, the pintles engaging in the lower ends of the grooves in the lowered position of adjustment of the said braces and engageable in the upper ends of the grooves in an elevated position of adjustment in which position of adjustment the arm rests are in their first mentioned position of adjustment,

and means adjustably mounted upon the side members of the upright frame movable into and out of position to close the lower portion of the groove in the respective side member and support the ends of the respective brace in the last mentioned position of adjustment of the brace.

11. A device of the class described comprising a supporting frame, a pair of arm rests hingedly connected to the sides of the frame and adjustable to position extending forwardly therefrom, a pair of chair legs hingedly connected to the arm rests adjacent the outer extremities thereof and adjustable to support the arm rests and also adjustable to a position extending in alinement with the arm rests, brace bars connected with the arm rests and adapted to support the same in their extended position of adjustment, a board connected to the frame and adjustable to position to serve as a back rest, when employing the device as a chair, and adjustable to position to serve as an ironing board when employing the device as an ironing stand, and a seat member connected with the board and having adjustable connection with the legs to be supported thereby when employing the device as a chair and to constitute a brace between the board and the legs when employing the device as an ironing stand.

In testimony whereof we affix our signatures.

OLIVER C. ARMSTRONG.
